UNITED STATES PATENT OFFICE

JOHN E. LYONS, OF TEXHOMA, OKLAHOMA

PIPE GRAB

Application filed August 23, 1929. Serial No. 387,923.

This invention relates to pipe grabs, and is particularly adapted for attachment to oil well towers for pulling pipe out of oil wells.

One of the objects of the invention is to provide a pipe grab of the character referred to, that will grip the pipe so that the same may be pulled in a straight line out of the oil well and furthermore to provide a second clamp on the bottom of the tower that will not only cause the upper grab to pull in spaced alinement with the well, but will also prevent the pipe from slipping back into the well in event the pulling grab should slip or otherwise be displaced from the pipe.

Further objects of the invention are to provide, in a manner as hereinafter set forth, a device of the character referred to, which is strong, compact and durable, thoroughly reliable for its intended purpose, very simple in its method of assembly, and comparatively inexpensive to manufacture and operate.

With the foregoing and other objects in view, the invention consists of a novel construction, combination and arrangement of parts as will be hereinafter more specifically described and illustrated in the accompanying drawings, wherein is disclosed an embodiment of the invention, but it is to be understood that changes, variations and modifications may be resorted to without departing from the spirit of the claims hereto appended.

In the drawings, wherein like reference characters denote corresponding parts throughout the several views:

Figure 1 is a fragmentary portion in side elevation of a tower surrounding an oil well and a pipe being withdrawn from the well with the grabs applied thereto in accordance with the present invention.

Figure 2 is a top plan view of the upper pulling grab.

Figure 3 is an end view of the upper pulling grab.

Figure 4 is a top plan view of the lower grab.

Figure 5 is an end view of the lower grab.

Referring to the drawings in detail, 10 indicates one of four vertically extending posts of an oil well tower of the conventional type,

The posts are reinforced by horizontal bars 11 in the conventional manner. It is to be understood that the oil well tower is erected over the hole so that the tower can be used for a derrick. Attached to the top of the tower in any conventional manner is a block and tackle that is used for pulling pipe from the well hole.

The lower pulley of the block and tackle is indicated at 12 and has a nook 13 on the lower end thereof. The operating rope for the block and tackle is indicated at 14 and extends from the ground so that it may be attached to a winch for applying power to the lower pulley 12.

The upper clamp indicated generally at 15 is to be attached to the pulley 12 in a manner presently to be described. The lower clamp 16 is adapted to be secured to the post 10 of the derrick adjacent the lower end thereof and presently to be described.

The upper clamp 15 is formed of a metal plate of suitable width and bent to a substantially U-shaped configuration. The upper leg 17 of the upper clamp is of greater length than the leg 18. The legs 17, 18 are braced in spaced relation to each other by a single bolt 19 extending through and secured to each leg. The bolt 19 is located at the approximate center of the upper leg 17 and adjacent the forward end of the lower leg 18. The legs 17, 18 are further braced adjacent the bight portion 20 by a pair of bolts 21, 22 that extend through and are secured to each of the legs.

The nuts 23, 24 on the upper end of the respective bolts 21, 22 also hold a cleat 25 in secured relation to the upper face of the upper leg 17. The cleat 25 has an eye 26 on one end and an upstanding hook 27 on its opposite end. The cleat 25 is disposed above the bight portion of the upper clamp 15. The lower ends of the pair of bolts 21, 22 hold a right-angled bracket 27 secured to the lower face of the lower leg 18. One of the legs of the bracket 27 is formed with an arcuate concavity 28. The radius of this may vary in accordance with the diameter of the pipe being handled and clamped.

On the forward end of the upper leg 17, 100

the body thereof is cut out to provide an arcuate concavity 29 having a radius of or substantially equal to the radius of the pipe being used. The edges surrounding the concavity 29 are beveled as is clearly shown in Figure 3 of the drawings to provide a knife edge 30 flush with the upper face of the upper leg 17. The forward edge of the lower leg 18 is provided with a transversely extending sleeve 31 preferably formed integral therewith.

The sleeve 31 is coextensive with the lower leg 18. The eyes of the clevis 32 straddle the ends of the sleeve 31 and are rockably connected therewith by a pin 33 that extends through the eyes of the clevis and through the sleeve 31. The pin 33 is detachable with respect to the sleeve and the eyes of the clevis. The pin 33 is formed with an eye 34 on one end, and is connected to one end of a chain 35 and the opposite end of the chain 35 is rigidly connected to a staple 36 formed on the side of the clevis so that when the pin 33 is withdrawn the clevis and pin will not become separated.

A lug 37 is formed on the side edge of the lower leg 18 and the forward edge thereof abuts against the rear edge of the clevis to prevent the same from swinging more than ninety degrees about the pin axis.

A movable triangular link 38 is confined in the bight portion 20 between the bolts 21, 22 and said bight portion. One section of the chain 39 is connected at one end to the link 38 and at its other end to a ring 40. Another section of chain 41 is connected at one end to the ring 40 and on the free end thereof is provided with a hook 42.

In applying the upper hook 15 to the pipe 43 that is being pulled from the well, the section of chain 41 is wrapped about the pipe and the hook 42 is secured in the link in the ring 40. The ring 40 is then connected to the hook 13 on the lower pulley 12 as will be clearly understood by referring to Figure 1 of the drawings. The clevis 31 is then disposed about the pipe 43 and is connected by means of the pin 33 to the forward end of the lower leg 18.

The arcuate concavity 29 on the upper leg 17 being in alignment with the clevis 31, will be disposed about the pipe 43 above the clevis 31. When power is applied for pulling the pipe in the direction of the arrows in Figure 1, the clamp 15 rocks upon the clevis 31 as a fulcrum and the knife edge 30 bites into the periphery of the pipe thereby providing a tight grip upon the pipe. The lower clamp 16 is similar in all respects to the upper clamp 15 with the exception of the dissimilarities to be noted below.

The clamp 16 is not provided with any cleat similar to that shown at 25 on the upper cleat. The lower clamp 16 is not provided with a right-angled bracket similar to

the bracket 27 on the upper clamp. The link 38 is similar in all respects to link 38 on the upper clamp and has extending therefrom a single cable 43 which may be a chain having a hook 44 on its outer free end.

The lower clamp consists of a U-shaped body portion having an upper leg 17' of greater length than the lower leg 18' and the bight portion 20'. The bottom clamp 16 has a single bolt 22' extending through the legs for reinforcing the same adjacent the bight portion 20'. Adjacent the forward end of the lower shorter leg 18' is a single bolt 19' similar in all respects to the bolt 19 of the upper clamp. The forward end of the lower leg 18' is formed with a sleeve 31' and the clevis 32' has the eyes thereof straddling the sleeve 31'.

The pin 33' extends through the eyes of the clevis and through the sleeve 31'. The pin 33' is formed with an eye 34' to which one end of the chain 35' is coupled and the other end of the chain 35' is secured to an eyelet 36' formed on the clevis for the purpose described in the upper clamp.

The forward edge of the upper leg 17' is provided with an arcuate cavity 29' having the knife edge 30' on its upper edge.

From the foregoing description taken in connection with Figures 4 and 5 of the drawings, it is believed that the points of similarity and dis-similarity have been described as compared with the upper clamp 15.

In the application of the lower clamp, the arcuate concavity 29' is disposed about the pipe 43' and the clevis 32' is disposed over the pipe 43' and the pin 33' is inserted through the eyes of the clevis and through the sleeve 31' whereby the pipe extends through the concavity 29' and the clevis 32'.

The chain 43 is wrapped about one of the posts 10 of the tower so that the clamp 16 will be above the casing of the well. The hook 44 is overlapped on the chain 43 and the clamp 16 is supported on the post 10. The lower clamp 16 permits the pipe 43' to be drawn upwardly, but in event the upper clamp should slip or the block and fall fail to function properly, on the downward fall of the pipe the clevis 32' will rock the upper leg 17' so that the knife edge 30' will bite into the pipe 43' and hold it securely from falling into the well.

The lower clamp 16 also provides for guiding the pipe 43' out of the well during the pulling operation on the upper clamp 15. A cord, cable or rope may be attached to the upper leg 17' of the upper clamp 15, not shown in the drawings, so that when the upper clamp 15 is used for lowering pipe into the well, the clamp 15 may be pulled upwardly from the pipe so that the operator will not have to climb to the top of the derrick every time a new grip is taken on the pipe to lower the same.

When the upper clamp 15 is used to lower a pipe into the well as distinguished from raising the pipe from the well, the lower clamp 16 may be used to hold the pipe while the upper clamp is being moved upwardly on the pipe to obtain a new grip.

It is to be understood that by describing in detail herein any particular form, structure or arrangement, it is not intended to limit the invention beyond the terms of the several claims or the requirements of the prior art.

Having described my invention, what I claim is:

- 15 1. A pipe clamp comprising a U-shaped body portion having legs of unequal length, a cable slidably connected in the bight portion of the body portion, a clevis detachably and pivotally engaged with the free end of the shorter leg, said longer leg having an arcuate concavity on the free end, said concavity having a knife edge on its upper edge adapted to grip the pipe when the body is rocked on the clevis by the power applied to the cable.
- 20 2. A pipe clamp comprising a U-shaped body portion having legs of unequal length, a cable slidably connected in the bight portion of the body portion, a clevis detachably and pivotally engaged with the free end of the shorter leg, said longer leg having an arcuate concavity on the free end, said concavity having a knife edge on its upper edge adapted to grip the pipe when the body is rocked on the clevis by the power applied to the cable, said knife-edge of the concavity disposed flush with the upper face of the longer leg, means secured between the legs to prevent them from bending.
- 25 3. A pipe grab comprising a U-shaped body having legs of unequal length, a cable secured to the bight portion of the body, a clevis pivotally connected to the end of the shorter leg of the body, the longer leg of the body having in its end a concavity.
- 30 4. A clamp comprising a U-shaped body including a pair of legs connected by a bight portion, a cable attached to the bight portion, the end of one of the legs having a concavity, and a clevis pivotally connected to the end of the other leg.

In testimony whereof I affix my signature.
JOHN E. LYONS.
